[57] CLAIM

The ornamental design for a cosmetic compact with two side buttons, as shown and described.

DESCRIPTION

FIG. 1 is a top plan view of a cosmetic compact with two side buttons showing our new design, the bottom
being the same;

FIG. 2 is a side elevational view, each side being the same; and,

FIG. 3 is a front elevational view, the rear being the same.
